UNITED STATES PATENT OFFICE.

HUGO COOK, OF DAYTON, OHIO.

CASH REGISTER AND INDICATOR.

SPECIFICATION forming part of Letters Patent No. 450,364, dated April 14, 1891.

Application filed October 23, 1890. Serial No. 369,063. (No model.)

To all whom it may concern:

Be it known that I, HUGO COOK, a citizen of the United States, residing at Dayton, in the county of Montgomery and State of Ohio, have invented certain new and useful Improvements in Cash Registers and Indicators, of which the following is a description, reference being had to the accompanying drawings, forming part of this specification.

10 My present invention consists, chiefly, in improvements on the machine described in my former patent, No. 445,671, dated February 3, 1891, to which reference may be made for a more detailed description of some of the

15 parts of the machine than will be necessary for the mere explanation of my improvements.

My improvements will be described in detail, and their novelty pointed out in the

20 claims.

In the accompanying drawings, Figure 1 is a side elevation of the machine; Fig. 2, a top plan view; Fig. 3, a front elevation with the front ends of the keys cut off. Fig. 4 is a sectional side elevation on a line through the middle of the machine. Fig. 5 is a sectional side elevation on a line to the left of the middle of the machine and looking toward the right. Fig. 6 is a front view of the total-registry part of the machine and the devices for resetting the wheels to zero. Fig. 7 is a vertical section of the same. Fig. 8 is a detail showing the transfer devices between two of the wheels and one of the locking-pawl

25 employed in connection therewith. Fig. 9 is a top plan view of the same. Fig. 10 is a side elevation of one of the registering-wheels of the total registry. Fig. 11 is a front elevation, partly in section, of the two trains of escapement and detent wheels, the transfer devices between them, and the two motor-wheels. Fig. 12 is a detail perspective of one of the detents and part of its co-operating escapement-wheel, the latter being in dotted

30 lines. Fig. 13 is a side elevation of an escapement-wheel and its co-operating detent support or wheel, with the hub of the escapement-wheel and the shaft on which they are mounted in section. Fig. 14 is a side elevation of the motor-wheel on the dollar side of the machine, with the spring-casing secured thereto in section to expose the motor-

spring. Fig. 15 is a side elevation of the motor-wheel on the cent side of the machine, showing the cam-disk of the transfer mechanism secured thereto and the winding-ratchet for its motor-spring. Fig. 16 is a perspective view of the two frames in which the wheels of the total registry are mounted and their associated devices. Fig. 17 is a detail 60 top plan view of the pawls for winding the motor-springs and their associated parts. Fig. 18 is a side view of one of the winding-ratchets and its operating-pawl when the ratchet is in such position as to render the 65 pawl inoperative.

The working parts of the machine are supported in a suitable frame-work, consisting in this instance chiefly of the side frames A A, the cross-pieces and rods connecting them, 70 and the supplemental side plates B B, mounted upon the frames A A and supporting the main portions of the registering mechanism. The front ends of the operating-keys are provided with the usual numbered finger-buttons, and their rear ends rest on the cross-piece C of the frame-work and carry the vertically-guided indicator-rods D, which are provided at their upper ends with the usual indicators E. The rods D are provided with 75 collars or projections F, co-operating with the supporting-bar G, to temporarily hold the indicators exposed at a glass-covered window in the upper part of the easing, (not shown,) all in the usual well-known manner.

As in my prior patent before referred to, the registering-wheel is actuated by a spring-driven motor-wheel whose movements are controlled and measured by an escapement mechanism operated by the keys. The motor-wheel, under tension of its spring, constantly tends to revolve and is geared directly or indirectly to the registering-wheel, so that whenever the motor-wheel is permitted to revolve it turns the registering-wheel a distance proportionate to the amount of its own movement. The motor-wheel is held in check and normally prevented from rotating under the influence of its spring by an escapement mechanism interposed between it and the 90 keys, and this mechanism, under the operation of different keys, permits the motor-wheel to rotate different degrees, and to thereby 95 turn the registering-wheel different degrees,

accordingly as one or another of the keys is operated. There are two of these motor-wheels in the machine, one for driving the cent-registering wheel and the other for the 5 dollar-registering wheel and its connected train of wheels with an escapement mechanism interposed between each motor-wheel and the set of operating-keys corresponding to it. The escapement mechanism in each case consists 10 of a train of escapement-wheels and a co-operating series of detents, all of which, excepting one, are also preferably supported on wheels or disks mounted on the same shaft as the escapement-wheels. These trains of 15 escapement and detent supporting wheels are illustrated and described in detail in my aforesaid patent. Their construction and general mode of operation are substantially the same in my present machine, so that only 20 such description of them as is necessary to an understanding of the improvements constituting my present invention will be given here.

The two trains of wheels are shown in Figs. 25 2, 3, and 11 and details of them in Figs. 12 and 13. A revoluble shaft G, Figs. 1, 2, 3, and 11, is journaled at its right-hand end in the side plate B and at its left-hand end in a bracket H, suitably supported on a cross- 30 piece of the frame-work. Tight upon the shaft G near its right-hand end is the cent-registering wheel I, having on its periphery a series of equidistant numbers in multiples of 5 from 0 to 95, while tight upon the opposite end of the shaft G, just to the left of the bracket H, is a pinion J, meshing with the spring-driven motor-wheel K, loosely mounted on the shaft L. This motor-wheel is impelled by its spring, hereinafter described, to revolve 35 in the direction of the arrow in Fig. 2, and to thereby turn the shaft G and wheel I in the opposite direction, as shown by the arrow on said wheel. The train of escapement-wheels A', A², A³, A⁴, and A⁵ and the 40 detent-supporting disks B', B², B³, and B⁴, co-operating with the first four of them, are mounted on the shaft G between the wheel I and pinion J. The detent B⁵, which co-operates with the escapement-wheel A⁵, is not 45 mounted upon a disk, but is secured to the side of the bracket H which supports the end of the shaft G.

As shown in Fig. 11, the wheel I has a laterally-extended hub or fixed sleeve on its left 55 side. The hub of the escapement-wheel A' is mounted and feathered upon this sleeve, so as to turn with it, but free to slide laterally upon it. The detent-disks B', B², B³, and B⁴ are loosely mounted directly on the shaft 60 G, and each of them has on its left side a laterally-extending hub or sleeve, upon which is mounted and feathered one of the escapement-wheels A², A³, A⁴, and A⁵, said hubs or sleeves filling the spaces between the faces of 65 the disks and serving to space them on the shaft G. The detents which co-operate with the teeth of the escapement-wheels are of the

shape shown in Figs. 12 and 13, from which it will be seen that each of them has two contact-faces—an outer one a and an inner one 70 a'—with a lateral passage or slot a² between them.

The wheel I, tight on the shaft G, geared to the motor-wheel K, is constantly tending to turn in the direction of the arrow on it and carry with it the escapement-wheel A'. This causes one of the teeth of the wheel A to press against the outer face of the detent on the disk B' and tend to turn the disk in the same direction. As the second escapement-wheel 80 A² is feathered on the hub of this disk B', said wheel A² will also be impelled in the same direction, and one of its teeth will be held pressed against the detent on disk B², tending to turn the latter in the same direction, 85 and so on through the entire train of wheels to the last escapement-wheel A⁵, whose teeth engage the stationary detent B⁵ on the bracket H. It will thus be seen that the power of the motor-wheel K is transmitted through the 90 pinion J, shaft G, wheel I, and the connected train of escapement and detent wheels to the last wheel A⁵, and that the engagement of the latter with the stationary detent B⁵ is what holds the entire train in check against the 95 impulse of the spring-motor.

When any escapement-wheel, as the one shown in Fig. 12, for instance, is slid to the left, its tooth which was in contact with the outer face a of the co-operating detent is 100 moved out of the plane of said outer face and into the plane of the inner face a', and the wheel, being thereby released, is revolved under the influence of the spring-motor until its said tooth strikes the inner face a', the wheel 105 I, of course, turning with it. When the wheel is slid to the right again, its said tooth is moved out of the plane of the inner face of the detent through the passage a², and is thereby entirely freed from the detent, and 110 the wheel I is turned on by the spring-motor until the next succeeding tooth of the wheel strikes the outer face a of the detent. It will thus be seen that in order to let a tooth of an escapement-wheel pass its co-operating detent to permit the wheel to turn a distance equal to that between two of its teeth the wheel is first slid to the left to free its engaged tooth from the outer face a of the detent 115 and is then moved to the right again to free 120 it from the inner face a' of the detent. Owing to the fact that the power of the motor constantly tends to turn the shaft G and wheel I in the direction of the arrow on the latter, and thereby holds the escapement-wheels all 125 pressed against the outer faces of their co-operating detents, when any escapement-wheel is released from its detent, in the manner described, the spring-motor turns the wheel I, through the medium of the pinion J and shaft G, until the next succeeding tooth of the escapement-wheel engages and is arrested by its co-operating detent. 130

The escapement-wheels have different num-

bers of teeth and are assigned different values. Thus the wheel A⁵ on the left has twenty teeth and is called the "five-cent wheel." When it is slid to the left and back to the right again, 5 to permit one of its teeth to pass its co-operating detent B⁵, it is turned one-twentieth of a complete revolution, and the shaft G and wheel I are turned an equal distance and five cents is registered on the wheel I. The wheel 10 A⁴ has only ten teeth, so that when it is moved to the left and back to the right, to permit one of its teeth to pass its co-operating detent on the wheel B⁴, it is turned one-tenth of a revolution and the shaft G and wheel I a like 15 distance. So the wheels A³ and A² each have five equidistant teeth and turn one-fifth of a revolution and register twenty cents on the wheel I whenever either is operated to permit one of its teeth to pass its co-operating 20 detent, while the wheel A' has only two teeth and is turned a half-revolution and registers fifty cents on the wheel I at each operation.

The above-described operation of the escapement and detent wheels is substantially 25 the same as that described in my aforesaid patent. The devices interposed between the operating-keys and the escapement-wheels for giving the latter the right and left movements to free their teeth from their detents, in the 30 manner described, are also the same as those described in my former patent. In brief, they consist of a series of slides 1, 2, 3, 4, and 5, carried in a slide-box M, supported by the frame-work, Figs. 2 and 3, and connected to 35 the escapement-wheels by centrally-pivoted levers 6, 7, 8, 9, and 10, flexibly joined to the slides at their lower ends and having forked upper ends engaging peripheral grooves in the hubs of the escapement-wheels. The 40 lower side of the slide-box M is provided with a vertical slot immediately above each key, and each slide has portions of its under side cut away to form pendent lugs, there being one lug for each key, with which the slide 45 co-operates. The lugs on the slides project from the right into the slots immediately above the respective keys with which they co-operate, as shown in Fig. 3. Each key has on its upper side, immediately beneath its 50 corresponding slot in the box M, a wedge N, Figs. 2, 4, and 5, which enters the slot in the box whenever the front end of the key is depressed and its rear end elevated. The wedge of the key has its bevel on its right side, 55 so that when the wedge of the key enters the slot in the box it will push to the right any slide whose lug projects into the slot, but will not move those slides whose lugs do not project into such slot. When any slide is moved 60 to the right in this manner, it will throw the upper end of the centrally-pivoted lever connected to it to the left, and thereby move the escapement-wheel to the left and free its engaged tooth from the outer face of its co-operating detent. When the key is released 65 and its wedge withdrawn from the slot in the box and the slide is returned to the left by

means hereinafter described, the escapement-wheel is thrown to the right again, its engaged tooth freed from the inner face of the detent, and the wheel permitted to turn until its next succeeding tooth engages the outer face of the detent. The arrangement of the lugs on the slides is such that the wedge of each key will move just the slide or slides which 70 are necessary to operate the proper escapement wheel or wheels to register the value of the key. Thus the slide 5 is the only one whose lug projects into the slot in the box M, which is immediately above the five-cent key, 75 so that when the five-cent key is operated and its wedge enters the slot in the box M the slide 5 will be the only one moved by it. This slide, through the medium of the pivoted lever 10, will operate the escapement-wheel A⁵ 80 to permit one of its teeth to pass the detent B⁵ and the shaft G and wheel I to be turned one-twentieth of a revolution to register five cents. The slide 4 will be the only one projecting into the slot above the ten-cent key, 85 so that upon operating that key the escapement-wheel A⁴ will be so moved as to permit one of its teeth to pass the detent on the wheel B⁴ and the wheel I to be turned one-tenth of a revolution. The slides 4 and 5 will 90 both project into the slot above the fifteen-cent key, so that the escapement-wheels A⁴ and A⁵ will both be moved to permit one tooth of each to pass its co-operating detent and to thereby permit the wheel I to be turned both 95 100 a tenth and a twentieth of a revolution to register fifteen cents. In like manner the slide connected to the escapement-wheel A' projects into the slot over the fifty-cent key, while the slides 1, 2, and 5, connected to the 105 escapement-wheels A', A², and A⁵, project into the slot over the seventy-five-cent key, so that upon the operation of the latter key a tooth on each of those wheels will pass its co-operating detent, and the wheel I will be turned 110 a distance equal to the sum of a half, a fifth, and a twentieth of a revolution to register seventy-five cents, and so on, the combinations being such that each key will move the proper slides to effect the registration of its 115 value on the wheel I, all in the manner and by the means described in my aforesaid patent.

While both in this case and in my former patent the cent-registering wheel I is secured 120 on the shaft G and geared to the motor-wheel through the medium of said shaft and the pinion J, it is evident that such an arrangement is merely a convenient and not an essential one, for the wheel might have a separate 125 support and be independently geared directly or indirectly to the motor-wheel.

The train of dollar-registering wheels are mounted on a shaft G', Figs. 2, 3, 4, 5, and 11, in line with the shaft G and supported at its 130 left-hand end in the side plate B and at its right-hand end in a bracket H', supported on the same cross-piece of the frame-work which carries the bracket H. Tight upon the right-

hand end of the shaft G' just to the right of the bracket H' is a pinion J', meshing with a spring-driven motor-wheel K', loose on the shaft L and corresponding to the motor-wheel K of the cent-registering mechanism. The spring acting on this motor-wheel tends to revolve it in the direction of the arrow in Fig. 2, and to thereby turn the pinion J' and shaft G' in the opposite direction. Tight upon the opposite end of the shaft G' is a hub having a laterally-extending integral sleeve I', upon which is feathered the first of the escapement-wheels C'. The teeth of this wheel co-operate with the adjacent detent-supporting wheel D', which fits against the right-hand end of the sleeve I' and is loosely mounted directly on the shaft. This wheel D' has a laterally-extending hub or fixed sleeve on its right side, and on this sleeve is feathered the second escapement-wheel C², whose teeth co-operate with the detent-supporting wheel D², which in turn has an extended hub, upon which is feathered the third escapement-wheel C³. The teeth of this wheel co-operate with the detent-supporting wheel D³, upon whose hub is feathered the fourth escapement-wheel C⁴. The teeth of the wheel C⁴ co-operate with the detent on the wheel D⁴. The wheel D⁴ is loose on the shaft G' and has rigid with it on the same hub or sleeve a fifth escapement-wheel C⁵. The teeth of the latter co-operate with detents on the opposite ends of a curved rocking arm O, Figs. 3, 4, 5, and 11, on the end of a rock-shaft P, journaled at its opposite ends in the brackets H H', Fig. 3. Tight upon one end of a sleeve Q, loose upon this rock-shaft P between the brackets H and H', is a pinion R, meshing with the motor-wheel K'. Tight upon the opposite end of the sleeve Q is a pinion S, meshing with the primary wheel of the series of total-registering wheels, hereinafter described. One of the teeth of the escapement-wheel C⁵ is normally in engagement with one of the detents on the rocking arm O, the detents on the latter serving to hold the train of wheels from turning under the impulse of the motor, as does the stationary detent B⁵ in the case of the cent-registering train of wheels. Inasmuch as the wheel C⁵ is normally held stationary and the wheel D⁴ is rigidly secured to it, the detent on the wheel D⁴ is really the end of the train of escapements and detents and serves the same purpose as the fixed detent B⁵ of the cent train of wheels.

Whenever one of the escapement-wheels is moved to the right to disengage its tooth from the outer face of its co-operating detent and then back again to the left to disengage said tooth from the inner face of said detent, the wheel is allowed to turn under the influence of the motor-wheel until its next succeeding tooth engages the outer face of the detent. This permits the motor-wheel to turn the pinion R, and consequently the pinion S and the primary wheel of the total registry, the same part of a revolution that the escapement-

wheel has turned. It will be understood that the motor-wheel K' is constantly tending to turn the pinion J' and shaft G', but is held in restraint by the detent on the wheel D⁴, which latter is held stationary by the detents on the rocking arm O engaging a tooth of the escapement-wheel C⁵. The power of the spring is thus transmitted from the motor-wheel through the shaft G' to the sleeve tight on its left-hand end and thence back through the train of escapement and detent wheels to the wheel C⁵, which is held from turning by the detents on the arm O. This causes one tooth of each escapement-wheel to be constantly pressed against the outer face of its co-operating detent, so that when any one of said wheels is slid to the right and back to the left again one of its teeth passes the detent and the wheel turns a part of a revolution, the motor-wheel K' turning at the same time and turning the pinion R and the primary wheel of the total registry. The escapement-wheels C', C², C³, and C⁴ are shifted to the right and left upon the operation of the dollar-keys through the medium of a series of slides and centrally-pivoted levers, just as in the case of the cent-registering mechanism, before described.

So much of the machine as has been thus far described, excepting the rocking arm R, carrying the detents engaging the escapement-wheel C⁵, is substantially the same as that described in my former patent, about the only difference being that in the present case the motor-wheel K' is geared to the primary wheel of the total registry independently of the revoluble shaft upon which the escapement and detent wheels of the dollar series are mounted. In my former patent the primary registering-wheel is geared to a pinion on this shaft.

The first improvement to be now described relates to the transfer mechanism between the cent and dollar registering wheels, whereby the complete revolutions of the cent-wheel are transferred to and registered upon the dollar-wheel. This mechanism is shown in Figs. 2, 3, 4, 5, and 11. Upon the rock-shaft P, just to the right of the pinion S, is rigidly secured a pendent arm T, whose lower rear end is pressed by a spring against the periphery of what I term a "cam-disk" U, secured to the inner side of the motor-wheel K, Fig. 15. The periphery of this disk is divided into six spaces of equal length, and in each alternate space the periphery is cut away, so as to form three raised spaces and three depressed spaces. These spaces are of such length and the numbers of teeth in the gear of the motor-wheel and in the pinion J are such that the periphery of the motor-wheel and disk U moves the distance of one of the spaces while the motor-wheel is turning the pinion J, and consequently the shaft G and wheel I, one complete revolution. As illustrated in the drawings, there are ninety teeth in the gear of the motor-wheel and fifteen in

the pinion J, while the periphery of the disk U is divided into six spaces. Inasmuch as the lower rear end of the arm T is constantly pressed by its spring against the periphery 5 of the disk U it will at times rest in the depressed spaces and at other times on the raised spaces. As the motor-wheel and disk revolve and the end of the arm T drops into one of the depressed spaces, it rocks its shaft 10 P in one direction, and when, by the further revolution of the wheel and disk, it is raised out of the depressed space onto a raised space it rocks its shaft in the opposite direction. This rocking of the shaft P also rocks the 15 arm O on its opposite end and throws first one detent and then the other into engagement with the escapement-wheel C⁵. At each rocking of the arm O one tooth of the wheel C⁵ is released and this permits the spring- 20 impelled motor-wheel to turn the pinion J', shaft G', and the train of wheels on the shaft until the wheel C⁵ is arrested by another of its teeth engaging the opposite detent on the arm O. The turning of the motor-wheel not 25 only turns the pinion J', but also the pinions R and S on the sleeve Q, and the primary wheel of the total registry which meshes with the pinion S. The number of teeth on the escapement-wheel C⁵ and in the pinion R and 30 the gear of the motor-wheel are relatively such that upon each of these operations consequent upon the rocking of the shaft P the primary wheel of the total registry is turned just far enough to cause one dollar to be added 35 on said registry. My invention, so far as this transfer mechanism is concerned, is not limited to the details of construction and arrangement of the parts, the only essentials being the rocking arm O, having the detents 40 at its ends and rocked at regular intervals in the revolution of the motor-wheel K and the escapement-wheel C⁵, co-operating with said detents and geared to the motor-wheel K'. So far as the transfer mechanism alone 45 is concerned the wheel C⁵ might be tight on the shaft G' or mounted on an independent support and geared directly to the motor, for it is evident that its function as part of the transfer mechanism has nothing whatever to 50 do with its co-operation with the other wheels mounted on the shaft. So far as those wheels are concerned the detent on the wheel D⁴ corresponds to the fixed detent B⁵ of the cent train of wheels. If the wheel D⁴ were made 55 stationary, the escapement-wheel C⁵ could be removed from the shaft and the operation of the machine by the dollar-keys would remain precisely the same. It will therefore be understood that so far as the transfer mechanism 60 is concerned the escapement-wheel C⁵ need not be geared to the motor-wheel K' indirectly through the train of wheels connecting it to the shaft G', but might be independently supported and geared directly to the 65 motor-wheel.

Again, while I have shown and described the cam-disk U on the motor-wheel K as the

means for rocking the shaft P and arm O at regular intervals in the revolution of the wheel K to alternately engage the detents at 70 the opposite ends of the arm O with the escapement-wheel, yet I do not wish to be limited to such means for actuating the arm O, for my invention contemplates, broadly, the combination of the two motor-wheels, the 75 arm O, having the detents at its opposite ends and rocked at regular intervals in the revolution of the wheel K by any suitable means, and the escapement-wheel C⁵, co-operating with the detents at the ends of the arm O and 80 connected or geared directly or indirectly, to the motor-wheel K'. Even when a cam-disk is employed for rocking the shaft P and arm O it need not be secured to the motor-wheel K, but may be independently supported and geared directly or indirectly to the 85 wheel K, so as to be revolved by or with it. Again, under the construction I have shown and described the arm O is rocked to release one tooth of the escapement-wheel C⁵ only at 90 each complete revolution of the cent-registering wheel; but it is evident that if said wheel were arranged to register a dollar at each half-revolution the cam-disk could be constructed to rock the arm O at each of such 95 half-revolutions to transfer a dollar to the total registry.

The next feature of my invention relates to the method of winding the springs which drive the motor-wheels and regulating the 100 tension thereof, and is illustrated most clearly in Figs. 2, 4, 14, and 15. Both springs are alike in their relative location and arrangement, and I will first describe that employed for driving the motor-wheel K', Figs. 4 and 105 14. A coiled spring V is inclosed in a casing W, secured upon the side of the motor-wheel. The inner end of the spring is secured to a sleeve X, loose on the shaft L, which supports the motor-wheel, while the outer end of 110 the spring is secured to the inner side of the rim of the casing W, and the spring is so arranged that it will be wound up by turning the sleeve X in the direction of the arrow and will tend to turn the motor-wheel K' in 115 that direction. The sleeve X projects through the casing W and just outside the latter has secured on it a ratchet Y, Fig. 4, having in this instance six teeth. The motor-wheel K has secured to it a like spring-casing W', 120 Fig. 15, (slightly different in appearance, owing to the cam-disk U being formed integral with it,) containing a like coiled spring secured at its outer end to the casing and at its inner end to a sleeve loose on the shaft 125 L and carrying a ratchet Y' just outside the casing, as in the case of the motor K'. Carried by or integral with a sleeve Z, Figs. 2 and 4, loose on the shaft L, between the ratchets Y and Y', is a rearwardly-extending arm or 130 plate Z'. In a housing formed of a recessed plate Z², secured upon the upper side of the plate Z', Figs. 2 and 4, are confined two sliding pawls Z³ Z⁴, Figs. 2, 4, and 17. Spiral springs

confined between the rear ends of these pawls and the rear wall of the recessed plate Z^2 press them against the faces of the ratchets $Y Y'$, respectively. Pivoted between ears on the lower side of the plate Z^2 is the upper end of a link E' , whose lower end is pivoted between lugs on the upper side of a vibrating bar E^2 , Figs. 4 and 5, extending across and resting upon the upper sides of the operating-keys and hung at each end by side arms $E^3 E^4$ upon pivotal supports on the framework at $b b'$, Figs. 1, 4, and 5. It results from this construction and arrangement of the parts that when the finger-button on the front end of any key is depressed and the rear of the key is lifted the bar E^2 and link E' lift the plate Z^2 and cause the pawls Z^3 and Z^4 to turn the ratchets $Y Y'$ and wind up the springs.

Owing to the fact that the motor-wheel turns different distances upon the operation of keys of different values the springs are unwound more or less each time, according to the value of the key operated. Thus upon the operation of the five-cent key the motor-wheel K will move only a very short distance, while upon the operation of the seventy-five or the ninety-five cent keys it will turn much farther. It is therefore necessary that the spring for each motor should be kept wound up sufficiently to turn the motor far enough to register the value of the highest key in its series; but if the ratchet were turned and the spring wound an equal distance at each operation of any of the keys the spring would soon become wound up tight if the keys of lower values should be successively operated and the machine would become locked. To obviate this difficulty in my patent before referred to, the outer end of the spring was shown as attached to a friction-ring fitting the inside of the rim of the casing. This ring was held against the casing by friction, and when the tension of the spring reached a certain limit the ring would slip in the casing and relieve the spring. In the present case I accomplish the same result in a more efficient manner and by entirely different means. Engaging the forward face of the ratchet Y , as seen in Figs. 2 and 4, is a hooked holding-dog F' . The lower end of this dog is pivoted to a short arm F^2 , pivoted between ears upon the under side of a cross-piece F^3 of the frame-work. The dog F' is therefore free to move upward and downward, its movements being limited by the engagement of the front and rear portions of the arm F^2 with the under side of the cross-piece F^3 . Secured upon the upper side of the cross-piece F^3 is a strong flat spring F^4 , Fig. 4, whose rear end bears upon a pin on the side of the dog F' in such manner as to not only hold the dog in engagement with the ratchet but also to press it downward and pull the ratchet forward against the tension of the coiled spring V inside the casing W , Fig. 14, which tends to turn the ratchet backward. The relative strength of the two springs F^4 and V is such that when the latter is wound up until its ten-

sion passes a certain degree it will overcome the pressure of the spring F^4 on the dog F' and turn the ratchet Y backward a slight distance, 70 pulling the dog F' upward. The result of this backward movement of the ratchet is to bring the points of its teeth into such position that the pawl Z^3 , carried by the plate Z' , will in its lowest position rest just above and 75 upon the point of the tooth adjacent to it, as shown in Fig. 18, instead of catching under it, as in Fig. 4. When a key is operated and the bar E^2 , link E' , and plate Z' are lifted, the pawl Z^3 will ride idly over the face of the 80 tooth and not turn the ratchet; or if the stroke of the key gives it sufficient movement it may engage the next tooth above it and turn the ratchet slightly, but it cannot turn it far enough to cause a fresh tooth to be 85 caught by the dog F' , so that when the key is released the ratchet turns backward again. If the operated key, when the parts are in the position just described, is one of the higher values, the motor-wheel may turn far 90 enough to unwind the spring V and relieve its tension sufficiently to permit the spring F^4 to again overcome it and pull the ratchet slightly forward against the tension of the spring V , so that when the pawl Z^3 returns to 95 normal position it will catch under a fresh tooth of the ratchet, and upon the next operation of a key will turn the ratchet and wind up the spring again. If the operated key be one of lower value, it may not allow 100 the motor-wheel to move far enough to unwind the spring V sufficiently to allow the spring F^4 to overcome its tension and pull the ratchet forward, in which event the ratchet will remain stationary during the succeeding 105 operation of the keys until the motor has moved far enough to produce that result.

When the keys of higher value are successively operated, the motor moves far enough each time to cause the pawl to turn the ratchet and wind up the spring frequently; but when the keys of lower value are operated the motor moves a less distance and the pawl turns the ratchet less frequently. In any event the action of the spring F^4 causes the motor-spring to be maintained at the proper tension to always insure its turning the motor-wheel the full distance necessary to register the value of any operated key.

The motor-wheel K and ratchet Y' have 120 combined with them a dog G^2 and a spring corresponding to F^4 in the same manner as the motor K' and ratchet Y . This feature of my invention, in its broader scope, contemplates, broadly, the combination of the motor-spring and a tension-regulating spring co-operating with each other in the manner described without regard to the form of either of them or of their associated parts, or of the particular manner of combining them. In a somewhat more restricted scope it contemplates the broad combination of a motor-spring, a winder therefor, and a tension-regulating spring normally overcoming the ten-

sion of the motor-spring, but capable of being overcome by the motor-spring when the latter is wound beyond a given point to render the winder inoperative.

5 Another feature of my invention relates to the means for resetting the slides in the slide-box M after they have been shifted by the wedges on the keys entering the slots in the box and after the latter have been withdrawn therefrom. In my former patent two forms of devices for this purpose are described, one consisting simply of flat springs bearing against the outer ends of the two sets of slides and pressing them inward and the other consisting of cam-wedges engaging the outer ends of the slides, said wedges being lifted upon the operation of a key to permit the slide or slides moved by that key to be thrown outward, and falling upon the release of the key to force the slide or slides inward. In my improved construction the slides are reset by the positive movement of resetting-plates which force the slides inward upon the release of an operated key. These resetting-plates H² H³ 25 are shown in Figs. 2, 3, 4, and 5. They are in this instance pivotally hung at their upper ends between lugs c c upon the inner faces of the side plates B B of the frame-work, Figs. 2 and 3, and their lower inner faces rest 30 against shoulders c' on the upper sides of the slides near their outer ends. The plate H² at the right side of the machine bears against the slides 1, 2, 3, 4, and 5 of the cent series, while the plate H³ in the left side of the machine bears against the slides of the dollar series. 35 Flexibly connected to each of the plates H² H³ near its middle is a rearwardly-extending rod I² I³, the rear ends of the two rods being connected to the upper side of the 40 vibrating cross-bar E², before described, near its middle at d, Figs. 1, 4, and 5. When the vibrating bar E² is lifted by the operation of a key, the point d is brought nearer the plates H² H³ than it is when the bar is at rest and 45 the rods I² I³ swing the plates H² H³ outward or permit the slides moved by the operated key to push them outward. When the operated key is released, the resetting of the bar E² causes the rods I² I³ to pull the plates inward again and reset the slides, as will be 50 readily understood. This feature of my invention is not restricted to the form of the plates or the method of supporting them, it being sufficient that they are capable of the 55 necessary movements to permit the operation of the slides by the keys and to reset them after the operated key or keys are released and are so connected with the vibrating bar common to the series of keys as to be given 60 their resetting movement by it.

The next feature of my invention relates to the train of wheels constituting the total registry, and more particularly to the transfer devices between said wheels, the locking devices for one set of them, and the means for resetting the wheels to zero. A top plan view 65 of these wheels and the frames in which they

are carried is shown in Fig. 2, a front view at an angle in Fig. 6, a vertical section in Fig. 7, a side elevation in Fig. 5, a sectional side elevation in Fig. 4, and details in Figs. 8, 9, and 10. The upper set of wheels L', L², L³, and L⁴, suitably separated by their hubs on fixed sleeves, are loosely mounted on a shaft J², supported in a frame J³, carried upon the front side of the cross-piece F³ of the main frame-work of the machine. The frame J³ consists, chiefly, of its two opposite side plates and the front and rear cross-plates uniting them, (see Fig. 16,) by the rear one of which cross-plates it is secured to the cross-piece F³ of the frame-work, Fig. 5. The first of the upper set of wheels L' is a simple pinion and meshes with the pinion S on the sleeve O, loose on the rock-shaft P and carrying the pinion R, meshing with the motor-wheel K', as heretofore described. I have referred to this pinion L' as the primary wheel of the total registry, since it is through this wheel that the movements of the motor-wheel K' are communicated to the rest of the wheels of the total registry. Each of the other wheels L², L³, and L⁴ of the upper set consists of a pinion similar to L', but having a wider face, and carries on its right-hand side a star-toothed wheel d', Fig. 8, for a purpose hereinafter explained. Fitting between the side plates of the frame J³ is a rocking frame or cradle J⁴, (see Figs. 16, 6, and 7,) loosely mounted on a shaft J⁵, supported at its ends in the side plates of the frame J³. This swinging frame J⁴ consists of its two side plates and the cross-bars d² d³, uniting their front and rear ends. Pivoted by side arms d⁴ between ears d⁵ on the upper rear edge of the side plates of the frame J³, Fig. 16, is a locking-bar J⁶, having a sharp lower edge, as seen in Fig. 4. The bar J⁶ is provided with a handle d⁶. When the bar is in its normal position, its lower edge is immediately above the pinions L', L², L³, and L⁴ of the upper set, and the lower rear ends of its side arms d⁴ fit in notches on the upper side of the rear cross-bar d³ of the swinging frame J⁴ and lock that frame from movement, as seen in Fig. 16. 115 When the handle d⁶ is pulled forward, the lower edge of the bar J⁶ is thrown downward and fits between the teeth on the pinions beneath and locks them from movement. At the same time the rear ends of its arms d⁴ are thrown up out of engagement with the cross-bar d³ of the frame J⁴, and the latter is free to rock on its pivotal shaft J⁵, its rear end rising and its front end falling. Its rear end in rising moves its cross-bar d³ in front 120 of the lower ends of the side arms d⁴ of the locking-bar J⁶, so that said bar cannot be thrown upward again and the pinions freed until the frame J⁴ is restored to normal position, as will be understood from Fig. 16. It 125 will thus be seen that when the frame J⁴ is in its normal position it is locked by the arms d⁴ of the bar J⁶, and that when the latter is moved into engagement with the pinions

the frame J^4 is released and in turn locks the bar J^6 , so that the latter cannot be moved to release the pinions until the frame J^4 is restored to normal position, all for a purpose hereinafter explained. The rear cross-bar d^3 of the frame J^4 also has a sharp upper and forward edge which engages and locks the pinions when the front end of the frame J^4 is lowered, so that upon pulling forward the handle of the locking-bar J^6 the pinions are first locked by said bar and then by the bar d^3 of the frame J^4 . Supported in upwardly-extending ears on the side plates of the frame J^4 is a revoluble shaft J^7 , whose outer ends project out through circular openings f^f' in the side plates of the frame J^3 , as shown in Fig. 7. Loosely mounted upon the shaft J^7 are the train of registering-wheels $M^1 M^2 M^3 M^4$ of the lower set. Each of these wheels of the lower set is composed of several wheels and disks integral with each other or rigidly secured together. The central portion constitutes the registering-wheel proper and bears on its periphery a series of numbers in multiples of one, from 0 to 9, inclusive. To the right side of the central portion of the wheel is secured a pinion e' , and to the left side two disks $e^2 e^3$, the inner one e^2 being in this instance of smaller diameter than the outer one and having a notch e^4 cut in its periphery at one point, Fig. 8. The disk e^3 has a tooth e^5 projecting from its periphery opposite the notch e^4 in the disk e^2 . The pinion e' of the right-hand one of the wheels M' normally meshes with the pinion L' , which constitutes the primary wheel of the series and meshes constantly with the pinion S on the sleeve Q , geared to the motor-wheel K' , so that the movements of the motor are transmitted directly to the wheel M' and the latter is turned at each operation of a key a distance sufficient to register its value. Likewise it is turned one number every time the transfer mechanism between the cent and dollar trains of wheels is actuated by a complete revolution of the cent-registering wheel, in the manner heretofore described.

The pinion secured to the right side of the wheel M^2 normally meshes with the pinion L^2 of the upper train of wheels. The disk e^3 , secured to the left side of the wheel M' , is also in line with the pinion L^2 , and at each complete revolution of the wheel M' its tooth e^5 turns the pinion L^2 and moves forward one number the wheel M^2 , whose pinion e' , as before stated, meshes with the pinion L^2 . In like manner at each complete revolution of the wheel M^2 its toothed disk e^3 will turn the pinion L^3 and move forward the wheel M^3 one number, and so on to the end of the series, thus adding on the wheels M', M^2, M^3 , and M^4 the total registration, not only of the dollar-keys, but also all the dollars registered by the revolutions of the cent-wheel, the remaining amount, less than a dollar, appearing upon the cent-wheel.

For the purpose of locking the wheels L' ,

L^2 , L^3 , and L^4 at all times, excepting at the moment they are being turned by the co-operating single-toothed disks e^3 on the wheels of the lower set, I provide a series of locking-pawl O' , Figs. 4, 6, and 8, strung upon the pivotal shaft J^5 of the frame J^4 , one for each of the first three wheels of the lower set and the co-operating wheels L^2 , L^3 , and L^4 of the upper set. The inner disk e^3 on the left side of each wheel of the lower set is arranged in the same plane as the star-toothed wheel d' of its co-operating wheel in the upper set. One of the locking-pawl O' , as shown in Figs. 4 and 8, extends up between each of the disks e^2 and its adjacent star-toothed wheel d' . A point on the forward side of the upper end of the pawl normally rests on the periphery of the disk e^2 and holds its rear rounded side between two of the teeth on the wheel d' , thereby locking said wheel and the pinion to which it is secured from movement. When, however, the wheel to which the disk e^2 is secured (not shown in Figs. 4 and 8) completes a revolution and the tooth on its disk e^3 engages the co-operating pinion of the upper set, the notch e^4 in the disk e^2 , which is opposite the tooth on the disk e^3 , is brought under the point on the forward side of the pawl O' , which allows the pawl to fall or be moved away from the star-toothed wheel d' , so that the tooth on the disk e^3 may turn the pinion to which the wheel d' is secured and cause it to turn forward one number the next wheel in the lower set. As the disk e^2 moves on, its notch e^4 is carried from under the point of the pawl, and the rear rounded face of the latter is forced back between two of the teeth on the wheel d' and locks said wheel and its pinion, as before.

When it is desired to turn the wheels M', M^2, M^3 , and M^4 back to zero, as at the end of a day's business, when the amount registered on the wheels has been noted and the machine is to be set for another day's business, the handle d^6 of the locking-bar J^6 is pulled forward, thereby throwing the lower edge of the bar into engagement with the pinions $L' L^2, &c.$, and locking them, and at the same time releasing the rear cross-bar d^3 of the frame J^4 . The front end of this frame is now thrown downward, a handle f^3 , Figs. 6, 7, and 16, formed integral with one of its side plates, being provided for this purpose. The downward movement of the front end of the frame J^4 carries the lower train of wheels away from the upper set and disengages the pinions e' from the pinions $L' L^2, &c.$ The wheels $M', M^2, &c.$, are then free to be turned on the shaft J^7 . In my former patent I have described no way of turning the wheels back to zero excepting by the fingers of the operator; but in my present application I have illustrated means for resetting them by a single revolution of the shaft upon which they are mounted.

As shown in Fig. 7, the left side of each of the wheels M', M^2, M^3 , and M^4 has a circular

recess g about the shaft J^7 , and projecting into the recess from its inner side in line with the shaft is a short pin or projection g' . The shaft J^7 is provided with a series of co operating pins g^2 , one in each recess, but near the outer side thereof when the shaft is in its normal position, and hence out of the path of travel of the pins g' . When the shaft J^7 is slid to the right, however, the pins g^2 on the shaft are brought into the same vertical plane as the pins g' , so that if the shaft is revolved its pins will engage the pins g' and pick up the wheels and cause them to turn with the shaft. (This much of the resetting mechanism is old and not of my invention.) The left-hand end of the shaft J^7 is screw-threaded and has a nut K^2 on it, and between this nut and the adjacent side plate of the frame J^4 is confined a spiral spring K^3 , which presses the nut K^2 and shaft J^7 to the left. The opposite end of the shaft J^7 extends through the side plate B of the machine, having a flexible joint interposed in it at K^4 to accommodate it to the movements of the swinging frame J^4 . On its outer end is a thumb-piece K^5 , by which it may be turned. When the frame J^4 is up and the pinions of the lower wheels are in mesh with those of the upper set, the flanged base of the nut K^2 does not coincide with the circular opening f in the side plate of the frame J^2 , so that the shaft J^7 cannot be pulled to the right to bring its pins g^2 into line with the pins g' in the recesses in the hubs of the wheels; but when the frame J^4 is thrown down to permit the wheels to be reset to zero the flange of the nut may be drawn into the opening f as the shaft J^7 is pulled to the right. The moving of the shaft J^7 to the right disengages a notch K^6 in its thumb-piece K^5 from a pin K^7 on the outer side of the plate B . The thumb-piece and shaft may then be turned forward, picking up and turning the wheels with them, and just as the wheels reach zero the notch K^6 will be brought into line with the pin K^7 again and the spring K^3 will snap the shaft back to the left, leaving all the wheels at zero. Upon throwing up the frame J^4 by means of the handle f^3 the pinions of the wheels in the lower set are brought into mesh with those of the upper set again, and the machine is ready to begin another day's operations. After the wheels have been reset to zero it is necessary that the frame J^4 be thrown up again and the pinions of the lower wheels brought into mesh with those of the upper set, as above described, before any of the keys of the machine are operated, for inasmuch as the pinions of the upper set of wheels are locked from movement by the locking-bar J^6 and rear cross-bar d^3 of the frame J^4 during the whole time the latter is down the motor-wheels could not move and the values of the keys operated would not be registered; but the proprietor or party taking off the registry of the machine and resetting the wheels to zero is liable to forget to throw up the frame J^4 and bring the two sets of wheels into gear again. I have

therefore provided a locking device which automatically locks the entire machine from operation as soon as the frame J^4 is thrown down, holds it locked so long as the frame remains down, and automatically unlocks the machine and permits the keys to be operated as soon as the frame is thrown up and the two sets of wheels brought into gear with each other again. This locking device is an exceedingly simple affair, both in construction and mode of operation, and is shown in Fig. 5. It consists of a bell-crank arm O^2 , hung loosely on the shaft L , which supports the motor-wheels. Its lower vertical arm is normally pulled rearward by a spiral spring O^3 , so that its lower end hangs immediately in rear of and above the flange on the lower rear side of the vibrating bar E^2 , which extends across and rests upon the upper sides of all the keys. The front end of the upper horizontal arm of the bell-crank rests upon a rearward extension of one of the side arms d^4 of the locking bar J^6 above described. When said bar is thrown downward into engagement with the pinions L^1 L^2 , &c., the rear extension of its arm d^4 is thrown upward. This lifts the front end of the horizontal arm of the bell-crank and throws the lower end of its vertical arm forward over the flange on the vibrating bar E^2 , so that said bar is thereby held from upward movement and locks all the keys of the machine from operation. When it is remembered that the throwing down of the frame J^4 , after it has been released by the arms d^4 of the bar J^6 , locks said bar J^6 and prevents its being moved upward again until the frame J^4 is again thrown upward and the pinions of the two sets of wheels brought into mesh, it will be readily seen that the whole machine is effectually locked so long as the frame J^4 remains down and the wheels are out of gear with each other. When the frame is thrown up again and the bar J^6 moved up to release the pinions of the upper set, the rear extension of the arm d^4 is thrown downward and the spring O^3 pulls the vertical arm of the bell-crank O^2 rearward and releases the bar E^2 and the operating-keys.

The locking device I have just described is a simple, convenient, and effective one for the purpose; but this feature of my invention is not restricted in its broader scope to any particular form and arrangement of lock for the purpose described, but contemplates broadly the combination of a registering-wheel, its prime mover as a driving-pinion, from which it may be disengaged, and a lock of any sort which automatically locks the machine from operation when the registering-wheel is disengaged from the driving-pinion or prime mover.

Again, while I have described a lock which operates automatically to lock the keys upon the disengagement of the registering-wheels from their driving-pinions, yet, as has heretofore been explained, the essential thing is that the machine shall be locked when regis-

tering-wheels are disengaged from their driving pinion or pinions, so that during the time they are disconnected from the operative parts of the machine it will be impossible to 5 operate any keys and lose the registry of their values. It is therefore evident that while an automatic lock is the most convenient and desirable, yet a hand-lock might be provided and placed under the control of the registering wheel or wheels in such manner that the latter could not be disengaged from their driving-pinion until said lock had been operated to lock the keys. For instance, in the machine described in this application a very 15 simple locking device might be interposed between the rocking frame J^4 , which carries the registering-wheels, and the vibrating bar E^2 overlying the keys, so that when the device was operated to lock the keys the frame would 20 be unlocked and when it was operated to lock the frame the keys would be unlocked. The broad scope of my invention contemplates all such contrivances as these, for it is evident that whether or not they are as convenient 25 and desirable as an automatic lock, they still perform the essential duty of such lock and accomplish the same important and desirable result—viz., they lock the keys when and while the registry of the machine is disconnected from its actuator and prevent the keys 30 being operated without their values being registered.

Again, when the locking device is automatic, it may be operated either directly from 35 the registering-wheels or the frame in which they are mounted; or it may be operated from an independent device, as the locking-bar J^6 , which locks the frame J^4 . For instance, where a locking-arm like the bell-crank arm 40 O^2 is employed, its front end may be made to engage the rear side of the frame J^4 , instead of an arm of the locking-bar J^6 , so that when the frame J^4 is lowered its rear end will lift the horizontal arm of the bell-crank and throw 45 its lower end forward over the flange on the bar E^2 , as will be readily understood.

The remaining feature of my invention relates to the operating-keys. Heretofore in machines of this class the keys have usually 50 consisted of simple levers fulcrumed between their ends, generally at a point between their middles and front ends. This gave a short quick stroke to their front ends and a long and faster stroke to their rear ends, with a 55 consequent loss of power in the work which their rear ends were required to do. In addition to the loss of power the very quick stroke of their rear ends was objectionable in many classes of machines.

60 My improved keys each consist of two levers $P' P^2$, Figs. 1, 4, and 5, fulcrumed at their adjacent ends side by side upon a horizontal shaft P^3 , extending across the lower front side of the machine. The levers P' carry at their front 65 ends the usual numbered finger-buttons, while the levers P^2 carry at their rear ends the vertical tablet-rod heretofore described. A tog-

gle composed of two links $Q' Q^3$ is interposed between each lever P^2 and a fixed point of the frame-work—in this instance a shaft Q^3 , 70 extending across the lower part of the machine from one side frame to the other. The central joint of this toggle is bent forward and connected by a link R' to a lug on the under side of the lever P' just in front of its fulcrum. When the front end of the lever P' is depressed, the link R' forces the central joint of the toggle rearward, thereby straightening the toggle and lifting the lever P^2 . Owing to the relative position of the parts the movement of the lever P^2 is much faster at first 80 than it is later, and as the toggle becomes nearly straight the stroke of the lever P^2 becomes very slow and powerful. This is especially advantageous in my improved machine, 85 for the resistance offered by the spring of the motor increases as the lever P^2 and vibrating bar E^2 rise, so that the slow and powerful stroke of the key is had when the spring has been put under greatest tension and offers the 90 most resistance. This improved form of key, while perhaps peculiarly applicable to and advantageous in my machine, may be employed in many other styles of cash-registers.

There may be combined with the cent series of keys any of the well-known or suitable forms of stops or key-locks for the purpose of preventing the simultaneous operation of two or more keys of the series.

The machine is also provided with a key-arrester, which compels the full and complete stroke of the operated keys in each direction. A well-known form of such key-arrester and its combination with the operating-keys are illustrated in Fig. 1; but as its particular construction and mode of operation form no part of my present invention it need not be described.

Having thus fully described my invention, I claim—

1. In a registering-machine, the combination of the two spring-impelled motor-wheels, a cent-registering wheel driven by the first and a dollar-registering wheel driven by the second, a rocking arm rocked at regular intervals in the revolution of the first motor-wheel, a detent at each end of said arm, and an escapement-wheel co-operating with said detents and geared to the second motor-wheel, substantially as and for the purpose described.

2. In a registering-machine, the combination of the two spring-impelled motor-wheels, a cent-registering wheel driven by the first and a dollar-registering wheel driven by the second, a rock-shaft rocked at regular intervals in the revolution of the first motor-wheel, an arm secured to said shaft, a detent at each end of said arm, and an escapement-wheel co-operating with said detents and geared to the second motor-wheel, substantially as and for the purpose described.

3. In a registering-machine, the combination of the two spring-impelled motor-wheels, a cent-registering wheel driven by the first

and a dollar-registering wheel driven by the second, a rocking arm rocked at regular intervals in the revolution of the first motor-wheel, a detent at each end of said arm, a revolute shaft geared to the second motor-wheel, and an escapement-wheel mounted on said shaft and co-operating with said detents, substantially as and for the purpose described.

10 4. In a registering-machine, the combination of the two motor-wheels, a rocking arm rocked at regular intervals in the revolution of the first motor-wheel, a detent at each end of said arm, a revolute shaft geared to the second motor-wheel, an escapement-wheel loosely mounted on said shaft and co-operating with said detents, and a train of escapement-wheels and detents mounted on said shaft and interposed between it and said 15 first-mentioned escapement-wheel, substantially as and for the purpose described.

5 5. In a registering-machine, the combination of the two motor-wheels, a cent-registering wheel geared to the first motor-wheel, a 20 rock-shaft rocked at each complete revolution of the cent-registering wheel, an arm secured to said shaft, a detent at each end of said arm, an escapement-wheel geared to the second motor-wheel and co-operating with 25 said detents, and a registering-wheel geared to said second motor-wheel, substantially as and for the purpose described.

6 6. In a registering-machine, the combination of the two motor-wheels, a revolute shaft 30 geared to the first motor-wheel, a cent-registering wheel secured to said shaft, a train of escapement-wheels and detents mounted on said shaft and interposed between said registering-wheel and a fixed detent, a rock-shaft 35 rocked at each complete revolution of said registering-wheel, an arm secured to said shaft, a detent at each end of said arm, a revolute shaft geared to the second motor-wheel, an escapement-wheel loosely mounted 40 thereon and co-operating with said detents, a train of escapement-wheels and detents mounted on said shaft and interposed between it and said first-mentioned escapement-wheel, and a train of registering-wheels geared to 45 the second motor-wheel, substantially as and for the purpose described.

7 7. In a registering-machine, the combination of the two spring-impelled motor-wheels, a cent-registering wheel driven by the first 50 and a dollar-registering wheel driven by the second, a cam-disk revolute with the first motor-wheel, a rocking arm rocked by said cam-disk, a detent at each end of said arm, and an escapement-wheel co-operating with 55 said detents and connected with the second motor-wheel, substantially as and for the purpose described.

60 8. In a registering-machine, the combination of the two spring-impelled motor-wheels, a cent-registering wheel driven by the first 65 and a dollar-registering-wheel driven by the second, the cam-disk revolved by the first mo-

tor-wheel, a rock-shaft rocked by said disk, an arm rocking with the shaft, a detent at each end of said arm, and an escapement-wheel co-operating with said detents and connected with the second motor-wheel, substantially as and for the purpose described.

9. In a registering-machine, the combination of the two spring-impelled motor-wheels, 70 a cent-registering wheel driven by the first and a dollar-registering wheel driven by the second, a cam-disk revolute with the first motor-wheel, a rock-shaft rocked by said disk, an arm secured upon said rock-shaft and provided with a detent at each end, and an escapement-wheel co-operating with said detents and connected to the second motor-wheel, substantially as and for the purpose described.

80 10. In a registering-machine, the combination of the two spring-impelled motor-wheels, a cent-registering wheel driven by the first and a dollar-registering wheel driven by the second, a cam-disk secured to the motor-wheel, a rock-shaft rocked by said disk, an arm secured upon said rock-shaft and provided with a detent at each end, and an escapement-wheel co-operating with said detents and geared to the second motor-wheel, substantially as and for the purpose described.

85 11. In a registering-machine, the combination of the two spring-impelled motor-wheels, a cent-registering wheel driven by the first and a dollar-registering wheel driven by the second, a cam-disk secured to the first motor-wheel, a rock-shaft rocked by said disk, an arm secured to said rock-shaft and having a detent at each end, an escapement-wheel co-operating with said detents and geared to the 90 second motor-wheel, and a train of registering-wheels geared to said second motor-wheel, substantially as and for the purpose described.

95 12. In a registering-machine, the combination of the two spring-impelled motor-wheels, a cent-registering wheel driven by the first and a dollar-registering wheel driven by the second, a cam-disk revolved by the first motor-wheel, a rocking arm rocked by said cam-disk and having a detent at each end, a revolute shaft geared to the second motor-wheel, an escapement-wheel mounted on said shaft and co-operating with the detents on the rocking arm, and a registering-wheel 105 110 115 geared to the second motor-wheel, substantially as and for the purpose described.

13. In a registering-machine, the combination of the two motor-wheels, a cam-disk revolved by the first of said wheels, a cent-registering wheel geared to said motor-wheel, a rock-shaft rocked by the cam-disk, an arm secured to said shaft, a detent at each end of said arm, an escapement-wheel geared to the second motor-wheel and co-operating with 120 125 130 said detents, and a registering-wheel geared to said second motor-wheel, substantially as and for the purpose described.

14. In a registering-machine, the combina-

- tion of the two motor-wheels, the cam-disk revolute with the first of them, a rocking arm rocked by said cam-disk and provided with a detent at each end, a revolute shaft 5 geared to the second motor-wheel, an escapement-wheel loosely mounted thereon and co-operating with the detents on the rocking arm, and a train of escapement-wheels and detents mounted upon the revolute shaft and 10 connecting it with said first-mentioned escapement-wheel, substantially as and for the purpose described.
15. In a registering-machine, the combination of the two motor-wheels, a cam-disk revolute by the first of them, a revolute shaft 15 geared to said first wheel, a cent-registering wheel tight on said shaft, a train of escapement-wheels and detents mounted on said shaft between said registering-wheel and a 20 stationary detent, a rocking arm rocked by the cam-disk and provided with a detent at each end, a revolute shaft geared to the second motor-wheel, an escapement-wheel loose on said shaft and co-operating with the de- 25 tents on the rocking arm, a train of escapement-wheels and detents mounted on said shaft and connecting it with the first-mentioned escapement-wheel, and a registering-wheel geared to the second motor-wheel, sub- 30 stantially as and for the purpose described.
16. The combination of the motor-wheels K and K', the cam-disk U, secured to the motor K, the rock-shaft P, provided with the arm T, engaging the cam-disk and with the arm O, having the detents at its ends, and the escapement-wheel C⁵, geared to the motor K' and co-operating with the detents on the arm O, substantially as and for the purpose described.
- 40 17. The combination of the motor-wheels K and K', the cam-disk U, secured to the motor K, the revolute shaft G, geared to the motor K, the registering-wheel I, tight on the shaft G, the train of escapement-wheels and detents 45 mounted upon the shaft G and interposed between the wheel I and the stationary de- 50 tent B⁵, the rock-shaft P, provided with the arm T, engaging the cam-disk, and with the arm O, having a detent at each end, the revolute shaft G', geared to the motor-wheel K', the escapement-wheel C⁵, loose on said shaft and co-operating with the detents on the arm O, and the train of escapement-wheels and detents mounted on the shaft G' and 55 connecting it with the escapement-wheel C⁵, substantially as and for the purpose de- 60 scribed.
18. In a registering-machine, the combination of a motor-wheel, a revolute shaft 60 geared thereto, a train of escapement-wheels and detents mounted on said shaft and interposed between it and a relatively stationary detent, and a train of registering-wheels 65 geared to the motor-wheel independently of the revolute shaft, substantially as and for the purpose described.

19. In a registering-machine, the combination of a coiled motor-spring, a winder therefor, a series of operating-keys common to the winder for actuating the same whenever any key is operated, and a tension-regulating spring co-operating with the motor-spring and arranged to relieve the latter and render the winder inoperative when the motor-spring is wound beyond a given tension, substantially as described.

20. In a registering-machine, the combination of a motor-wheel, a coiled propelling-spring, a winder therefor, a series of operating-keys common to the winder for actuating the same whenever any key is operated, and a tension-regulating spring co-operating with the propelling-spring to relieve the latter and render the winder inoperative when said propelling-spring is wound beyond a given tension, substantially as described.

21. In a registering-machine, the combination of a coiled motor-spring, a winding-ratchet connected to its inner end, an actuating-pawl for the ratchet, a yielding holding-dog 90 for the ratchet, and a tension-regulating spring applied to the holding-dog and co-operating with the motor-spring in the manner and for the purpose described.

22. In a registering-machine, the combination of a motor-wheel, a coiled propelling-spring connected thereto at its outer end, a winding-ratchet to which the inner end of the spring is connected, an actuating-pawl for the ratchet, a yielding holding-dog for the ratchet, and a tension-regulating spring applied to the holding-dog and normally overcoming the tension of the motor-spring, but arranged to be overcome by the latter to permit the holding-dog to yield when the motor-spring is wound beyond a given tension, substantially as and for the purpose described.

23. In a registering-machine, the combination of a motor-wheel, a coiled propelling-spring, a winding-ratchet therefor, an actuating-pawl for the ratchet, a series of operating-keys, a movable bar common to all of said keys, a connection between said movable bar and actuating-pawl, a yielding holding-dog for the winding-ratchet, and a tension-regulating spring applied to said dog and co-operating with the motor-propelling spring in the manner and for the purpose described.

24. In a registering-machine, the combination of two motor-wheels arranged side by side, a coiled propelling-spring for each of them, a winding-ratchet for each spring located on the inner side of the motor-wheel, an independent actuating-pawl for each ratchet, a series of operating-keys, a movable bar common to all of them, a connection between said single movable bar and the two actuating-paws, an independent yielding holding-dog for each ratchet, and an independent tension-regulating spring for each holding-dog, substantially as and for the purpose described.

25. In a registering-machine, the combination of the motor-wheel K' , the coiled propelling-spring W , the winding-ratchet Y , the actuating-pawl Z^3 , suitable means for supporting and moving said pawl, the holding-dog F' , and the spring F^4 , applied to said dog and co-operating with the motor-spring W in the manner described. 70
26. In a registering-machine, the combination of the motor-wheels K and K' , the propelling-springs W and W' , the winding-ratchets Y and Y' , the pawls Z^3 and Z^4 , a support therefor, the key-levers P^2 , the vibrating bar E^2 , the link E' , connecting said bar and the support for the pawls, the holding-dogs F^3 and G^3 , and the springs F^4 and G^3 , substantially as and for the purpose described. 75
27. In a registering-machine, the combination of the operating-keys, the vibrating bar E^2 , the slides in the slide-box M , the slide-resetting plates H^2 and H^3 , and the rods I^2 I^3 , connecting them with the vibrating bar E^2 , substantially as and for the purpose described. 80
28. In a registering-machine, the combination of a pinion, as L^2 , having on one side a toothed wheel d' , two co-operating disks e^2 and e^3 , the former having a notch e^4 in its periphery and the latter having a projecting tooth e^5 coincident with the notch e^4 , and a locking-pawl O' , interposed between the toothed wheel d' and notched disk e^2 and co-operating therewith in the manner described. 85
29. In a registering-machine, the combination of a pinion, as L^2 , having a toothed wheel d' secured thereto, a registering-wheel, as M' , composed of the numbered wheel e and the pinion e' and disks e^2 and e^3 , secured to it, the disk e^2 having a notch e^4 in its periphery and the disk e^3 having a projecting tooth e^5 coincident with the notch e^4 , a locking-pawl, as O' , interposed between the disk e^2 and the toothed wheel d' and co-operating therewith in the manner described, and a second registering-wheel, as M^2 , whose pinion e' meshes with the pinion L^2 , substantially as and for the purpose described. 90
30. In a registering-machine, the combination of the fixed frame J^3 , the rocking frame J^4 , the pinions mounted in the fixed frame, and the locking-bar J^6 , supported in the frame J^3 and arranged to lock the frame J^4 when in one position and to free said frame and lock the pinions when moved to another position, substantially as described. 95
31. In a registering-machine, the combination of the fixed frame J^3 , the rocking frame J^4 , the pinions mounted in the frame J^3 , and the locking-bar J^6 , pivoted in the frame J^3 and arranged to lock the frame J^4 when in one position and to free said frame and become locked by it when moved into position to lock the pinions, substantially as described. 100
32. In a registering-machine, the combination of the fixed frame J^3 , the rocking frame J^4 , carrying a train of registering-wheels, the driving-pinions mounted in the frame J^3 , the locking-bar J^6 , mounted in the frame J^3 and arranged to be moved into and out of engagement with said pinions to lock and unlock the same, and an arm, as d^4 , on the bar J^6 , 70 which locks the frame J^4 when the bar J^6 is disengaged from the pinions and releases said frame when the bar J^6 is moved into engagement with the pinions, substantially as described. 105
33. In a registering-machine, the combination of a driving-pinion, a registering-wheel driven thereby and capable of being disengaged therefrom, operating-keys to register different values, and a lock for locking said keys when the registering-wheel is disengaged from the driving-pinion, substantially as described. 110
34. In a registering-machine, the combination of a train of registering-wheels, a prime mover therefor, from which the registering-wheels may be disengaged, a series of operating-keys, and a lock for locking the keys from operation when the registering-wheels are disengaged from the prime mover, substantially as described. 115
35. In a registering-machine, the combination of a train of driving-pinions mounted in a fixed frame, a train of registering-wheels driven thereby and mounted in a movable frame, a series of operating-keys, and a lock for locking said keys when the movable frame is moved to disengage the registering-wheels from the driving-pinions, substantially as described. 120
36. In a registering-machine, the combination of a registering-wheel, its prime mover as a pinion, from which the registering-wheel may be disengaged, an operating-key, and an automatic lock which locks the key from operation while the registering-wheel is disengaged from its prime mover, substantially as described. 125
37. In a registering-machine, the combination of a train of driving-pinions, a train of registering-wheels driven thereby and which may be disengaged therefrom, a series of operating-keys, and an automatic lock which locks the keys and holds them from operation while the registering-wheels are disengaged from the driving-pinions, substantially as described. 130
38. In a registering-machine, the combination of a train of driving-pinions mounted in a fixed frame, a train of registering-wheels driven thereby and mounted in a movable frame, a series of operating-keys, and an automatic lock which locks the keys when the movable frame is released and moved to disengage the registering-wheels from the driving-pinions, substantially as described. 135
39. In a registering-machine, the combination of a train of driving-pinions mounted in a fixed frame, a train of registering-wheels driven thereby and mounted in a movable frame, a series of operating-keys, a movable bar common to said keys and moved by the

operation of any one of them, and a locking-arm automatically thrown into engagement with said movable bar to lock the same while the registering-wheels are out of engagement 5 with the driving-pinions, substantially as described.

40. In a registering-machine, the combination of a train of driving-pinions mounted in a fixed frame, a train of registering-wheels 10 driven thereby and mounted in a movable frame, a lock for the movable frame, a series of operating-keys, and a lock for locking said keys when the movable frame is released by its lock, substantially as described.

41. In a registering-machine, the combination of a train of driving-pinions mounted in a fixed frame, a train of registering-wheels driven thereby and mounted in a movable frame, a locking-bar for locking the pinions, 20 a series of operating-keys, and a lock operating to lock said keys when the locking-bar is thrown into engagement with the driving-pinions, substantially as described.

42. In a registering-machine, the combination of a train of driving pinions mounted in a fixed frame, a train of registering-wheels driven thereby and mounted in a movable frame, a locking-bar mounted in the fixed frame and operating in one position to lock 25 the movable frame and to release said frame and lock the pinions when moved to another position, a series of operating-keys, a movable bar common to said keys and moved by the operation of any one of them, and a locking-arm thrown into engagement with the movable bar to lock the keys by moving the locking-bar into engagement with the pinions to lock the latter and release the movable frame, substantially as described.

43. In a registering-machine, the combination of the fixed frame J³, the movable frame J⁴, the train of pinions mounted in the fixed frame and the train of registering-wheels mounted in the movable frame, the locking-bar J⁶, mounted in the fixed frame and provided with the locking-arm d⁴, the operating-keys and the vibrating bar E² overlying them, and the bell-crank locking-arm O², engaging the arm d⁴ at its upper front end and the bar 50 E² at its lower end, substantially as and for the purpose described.

44. In a registering-machine, the combination of a train of driving-pinions, a train of registering-wheels driven thereby and movable bodily toward and from said pinions, a revoluble shaft, on which the registering-wheels are mounted, and resetting devices interposed between the shaft and wheels, whereby upon moving the registering-wheels bodily 60 away from the driving-pinions said wheels may be reset to zero by a single revolution of the shaft on which they are mounted, substantially as described.

45. In a registering-machine, the combination of the revoluble shaft J⁷, provided with

the pins g², the registering-wheels loosely mounted thereon and provided with pins g' in their recessed hubs, the thumb-piece K⁵ on its outer end provided with a notch K⁶, co-operating with a pin K⁷ on the frame-plate 70 B, whereby upon disengaging the thumb-piece from the pin K⁷ and revolving the shaft J⁷ until the notch in the thumb-piece coincides with the pin K⁷ the registering-wheels will be reset to zero, substantially as described. 75

46. In a registering-machine, the combination of the revoluble shaft J⁷, provided with the pins g², the registering-wheels loosely mounted thereon and provided with the pins g' in their recessed hubs, a spring K⁸, pressing the shaft J⁷ in one direction with its pins g² out of the paths of the pins g', a thumb-piece K⁵ on the outer end of the shaft, and a pin K⁷ and co-operating notch or recess K⁶ between the thumb-piece and the stationary 80 plate B, whereby upon pulling the shaft to the right and disengaging the notch and pin and then revolving the shaft until the notch and pin re-engage the registering-wheels will be reset to zero, substantially as and for the 85 purpose described.

47. In a registering-machine, the combination of the fixed frame J³, having the train of driving-pinions mounted therein, the movable frame J⁴ within the frame J³, the revoluble 95 shaft J⁷, mounted in the movable frame and projecting at its ends through apertures in the frame J³, the registering-wheels loosely mounted on the shaft J⁷ and having recessed hubs provided with pins g', arranged to co-operate with pins g² on the shaft J⁷, and the flanged nut or collar K² on the shaft J⁷ outside the frame J³, said collar registering with the aperture in the frame J³ when the frame J⁴ is lowered to disengage the registering-wheels from the pinions, but not when it is up, whereby the shaft J⁷ is held from lateral movement except when the registering-wheels are disengaged from the pinions, substantially 100 as described. 105

48. In a registering-machine, an operating-key composed of two levers pivoted at their adjacent ends upon a common axis, a toggle interposed between one lever and a fixed point, and a link connecting the central joint 115 of the toggle with the other lever, substantially as described.

49. In a registering-machine, an operating-key composed of two levers P' and P², pivoted at their adjacent ends upon the shaft P³, a toggle O' O², interposed between the lever P² and a fixed point, and a link R', connecting the toggle with the lever P', substantially 120 as described.

50. In a registering-machine, the combination of the motor-wheel K', its propelling-spring V, the winding-ratchet Y, the actuating-pawl Z³, a support therefor, the operating-keys, the vibrating bar E², and the link E', connecting said bar with the support for 125 130

the pawl, substantially as and for the purpose described.

51. In a registering-machine, the combination of the motor-wheels K and K', their pelling-springs, the winding-ratchets Y' and Y, the pawls Z⁴ and Z³, a support therefor, the operating-keys, the vibrating bar E², and the

link E', connecting said bar with the support for the pawls, substantially as and for the purpose described.
